SAMUEL MARSH YOUNG, OF NEW YORK, N. Y.

ELECTRIC SIGNALING SYSTEM.

1,177,842.

Specification of Letters Patent.

Patented Apr. 4, 1916.

Application filed April 25, 1903. Serial No. 154,275.

To all whom it may concern:

Be it known that I, SAMUEL MARSH YOUNG, a citizen of the United States, residing at New York city, county and State 5 of New York, have invented certain new and useful Improvements in Electric Signaling Systems, of which the following is a specification.

My invention consists in a signaling system especially adapted for use on electric railways.

The object of my invention is to provide means whereby the condition of any section of a railway may be visibly, audibly or 15 otherwise indicated, as for instance, through the operation of semaphore arms, bells, lights, etc.

It has heretofore been proposed to divide an electric railway into a series of blocks 20 and to locate in each of such blocks a signaling device, normally held in the "clear" position by means of a magnet traversed by an electric current derived from a battery, the secondary of a transformer having its 25 primary in circuit with a source of current energy, or other source of electrical energy, and such signaling device adapted to be moved to the "danger" position when a car moves into a block, by the car shunting the 30 current from the source of energy around the signaling device and the signaling device subjected to the lifting-action of a counter-weight. This method of operation 35 of the signals is applicable to railways where the motive power is steam, or other source of energy carried on the car motor, but is not applicable to railways where the motive power is electricity, transmitted wholly or in part through the rails of the railway; 40 and, for the reason, that the currents employed for operating the car motors and signals must be kept distinct. For instance, in a railway operated by direct current energy, it is necessary that the signals be operated 45 by alternating or pulsating current energy; in the case where the car motors are operated by alternating current energy, that the signals also be operated by alternating current energy, but that the two currents be 50 of different frequency, or have different phase relation.

In the case where the car motors are operated by direct current, manifestly, it will be necessary to interpose devices in the system for preventing the direct current from influencing the devices adapted to be actu-

ated by an alternating current or vice versa. In former applications, Serial Nos. 139,543 filed January 19, 1903 and 144,548 filed February 21, 1903, filed by me, I have illustrated 60 the character and the use of such devices, and have also shown an arrangement of circuits whereby the direct and alternating currents employed make use of a common return.

I will now describe my invention as applied to a system employing a direct current for operating the car motors, and an alternating current for actuating the signaling devices, which system is intended as a modification of my application Serial No. 144,548.

The accompanying diagrams will serve to illustrate my invention. These diagrams are identical, with the exception that the diagram, Figure 2, illustrates the employment 75 of a reactance rail bond introduced between the ends of a divided track-rail, and across the rails, and which has for its object to make possible the use of both rails as a return for the direct current energy.

Referring to the drawings, 5 indicates a direct current generator; 6, outgoing conductor from which current may be taken to the car motor 7, through the instrumentality of a trolley pole or other contact device 8; 9, 10, rails upon which the motor moves. The rail 9 is divided into a series of block sections 9^a, 9^b, 9^c. In the diagram, Fig. 1, these sectional rails are shown as entirely separated. In Fig. 2, the ends of 90 the sections are shown as connected by reactance bonds 11. Corresponding bonds 11^a are connected across the rails and also a reactance bond 11^b interposed between the end of the rail section 9 and the dynamo 5. 95 The object of the reactance bonds is to prevent an alternating current from flowing between the block sections 9^a, 9^b, 9^c, or across the rails 9, 10, or from the section 9^a to the dynamo 5. The advantage of using the 100 inductance bonds is, that the resistance of the return circuit is thus materially reduced. And further, leakage of the alternating current between the rails is reduced to a minimum.

To operate the signals I employ the alternating generator 12, to which is connected the outgoing conductor 13, and return conductor 14. Connected across the conductors 13, 14, is the primary 15 of a transformer 16, the secondary 17 of which is connected across the tracks 9, 10. A trans-

former is located in each block. Connected across the tracks 9, 10, of each block is a primary 18 of a second transformer 19, the secondary 20 of which includes the coil of 5 a relay magnet 21. Mounted under the magnet is a pivoted armature 22.

23 indicates a source of electrical energy, which may be a battery, secondary, of a transformer, or other source of energy.

10 24 is a magnet; 25, contact point.

26 indicates a semaphore-arm mounted on standard 27. On one end of the semaphore-arm is a counter-weight 28, and connected to the opposite side of the arm is a rod 29, 15 which forms the armature of the magnet 24.

The operation of my device is as follows: Upon referring to the drawings it will be seen that the car motor occupies the center block 9^b. The effect of the motor upon entering a block is to short circuit the primary 18 of the transformer 19, thereby allowing the magnet 21 to drop its armature 22, and thus open the local circuit from the source of energy 23, to the magnet 24.

25 The effect of which is to permit the counter-weight 28 to lift the semaphore-arm 26 to the danger position, indicating that a car is on the block. When the car moves out of the block, the current in the secondary 20 30 of the transformer 19 energizes the magnet 21, which attracts its armature 22, closes the circuit from the source of energy 23, to the magnet 24, which attracts its armature 29, thus drawing the semaphore-arm 26 to the 35 "clear" position.

I do not limit myself in any wise to a system where the car motors are operated by a direct current and the signaling devices by an alternating current, as it will be evident to those skilled in the art that an alternating generator may be substituted for the generator 5, provided the frequency of alternations of current delivered from this generator be different from that from the generator 12. Under ordinary conditions of practice, I would make the alternations in the current from the generator 5, say 20 per minute, while that in the current from the generator 12, 112 per minute.

50 It is well understood that a transformer adapted to work with alternations at 20 per minute will not be influenced by a current with alternations of 112 per minute.

It is to be understood that the particular embodiment herein shown and described is only one form in which applicant's idea of means may be embodied and it is to be understood that applicant considers himself in no wise limited by the specific embodiment 55 shown.

In the claims of this application, and in referring to the separate currents employed for actuating the car motors and the signals, I have used the expression "differing in 60 character", and by this expression I wish

to have it understood that there must be a difference in electrical character and entirely irrespective of the relative strength of the two currents employed. As for instance, one current may be a direct current and the other an alternating current, or both currents may be alternating and differing in frequency or phase relation.

Having thus described my invention, I claim:—

1. In a signal system, the combination of 75 two lines of rails one of which is divided into block sections, reactance bonds connecting the ends of adjacent sections of said divided rail, a source of difference of potential at one end of each block section, a relay at the other end of each block section adapted to be operated by said difference of potential, a generator of power current of different character from said first source 80 adapted to deliver current through the cars to the rails of said system, a reactance bond connecting said divided rail with said generator, and a connection between the other rail and said generator, whereby both of 85 said rails may be adapted to convey substantially equal amounts of said power current and thereby substantially avoid the flow of stray power currents through the relays and whereby the independence of 90 each of said rails as a return conductor may be preserved, substantially as described.

2. In a signal system, the combination of 100 two lines of rails one of which is divided into block sections, reactance bonds connecting the ends of adjacent sections of said divided rail, a source of alternating current difference of potential at one end of each block section, a relay at the other end of each block section adapted to be operated 105 by said alternating current difference of potential, a generator of direct current power current adapted to deliver current through the cars to the rails of said system, a reactance bond connecting said divided rail with 110 said generator, and a connection between the other rail and said generator, whereby both of said rails may be adapted to convey substantially equal amounts of said power current and thereby substantially avoid the flow 115 of stray direct currents through the relays, and whereby the independence of each of said rails as a return conductor may be preserved, substantially as described.

3. In an electric railway, a trackway composed of two lines of rails each composed of rail lengths joined mechanically and electrically as usual, insulating material inserted at intervals in at least one of said lines of rails thereby forming block sections, a 120 signal controlling each block section, a source of signal current connected across the rails of each block, a translating device connected across the rails of each block, each translating device governing the signal for 125 130

the block to which it is connected, a car, a source of power current of different character from the signaling current, means connected to one terminal of said source of power current for conducting power current to one terminal of the motor of the car, connections from the other terminal of the motor of the car to both lines of rails, a reactance bond bridged around each of said insulating joints and forming an electrical path for the power current around said joint, a connection including a reactance bond from one line of rails to the other terminal of the source of power current, and a connection from said other terminal of the source of power current to the other line of rails independently of the first-named power current connection to said one line of rails, whereby two separate and independent return paths may be provided from the car motor to the source of power current, and whereby said paths may be adapted to return substantially equal amounts of power current while maintaining the separation of the blocks for signaling purposes, substantially as described.

4. In an electric railway, a trackway composed of two lines of rails each composed of rail lengths joined mechanically and electrically as usual, insulating material inserted at intervals in at least one of said lines of rails thereby forming block sections, a signal controlling each block section, a source of signal current connected across the rails of each block, a translating device connected across the rails of each block, each translating device governing the signal for the block to which it is connected, a car, a source of power current of different character from the signaling current, means connected to one terminal of said source of power current for conducting power current to one terminal of the motor of the car, connections from the other terminal of the motor of the car to both lines of rails, a reactance bond bridged around each of said insulating joints and forming an electrical path for the power current around said joint, a connection including a reactance bond from one line of rails to the other terminal of the source of power current, a connection from said other terminal of the source of power current to the other line of rails, and a reactance bond connected across the rails in each of said block sections, whereby two separate and independent return paths may be provided from the car motor to the source of power current, and whereby said paths

may return substantially equal amounts of power current while maintaining the separation of the blocks for signaling purposes, substantially as described.

5. In an electric railway, a trackway composed of two lines of rails, each line of rails composed of rail lengths joined mechanically and electrically as usual, except at least one line of rails having insulating members inserted therein at intervals forming block sections; signals, one governing the entrance to each block section, a source of signaling current, connections from the source of signaling current across the rails of each block section, translating devices, one controlled by each block section, each translating device controlling the signal governing entrance to the block section by which it is controlled, a car for movement upon the trackway including an electric propulsion motor having an incoming terminal and an outgoing terminal; a source of propulsion current for said propulsion motor having an out-going conductor and incoming conductor, the propulsion current being of a character different from the signaling current; the out-going conductor from the source of propulsion current connecting with the in-coming terminal of the propulsion motor, electric conductors connecting the out-going terminal of the propulsion motor with both track rails; means bridging each of the insulating members which prevents the flow of signaling current from block section to block section and which allows the propulsion current to flow from block section to block section through the line of rails having insulating members inserted therein at intervals; means adapted to electrically connect both rails at any point of any block section to the incoming conductor of the source of propulsion current which prevents the flow of signaling current between the two rails but allow the flow of propulsion current, whereby both of the rails of the particular block section selected may be used throughout their entire length as separate and independent returns for propulsion current to the incoming conductor of the source of propulsion current.

In testimony whereof, I affix my signature in the presence of two witnesses.

SAMUEL MARSH YOUNG.
